The ornamental design for a leash as shown and described.

DESCRIPTION

FIG. 1 is a perspective view of a leash of my new design in a clip connected state-of use;

FIG. 2 is a right side view thereof;

FIG. 3 is a left side view thereof;

FIG. 4 is a rear view thereof;

FIG. 5 is a front view thereof;

FIG. 6 is top view thereof;

FIG. 7 is a bottom view thereof; and,

FIG. 8 is right side view of the leash in a clip unconnected state-of-use.

In FIGS. 1-7 the leash is shown with a symbolic break in its length. FIG. 8 is shown with two symbolic breaks in its length. The appearance of any portion of the article between the break lines forms no part of the claimed design.
